Attorney.

UNITED STATES PATENT OFFICE.

EPHRAIM S. HECHT, OF NEW YORK, N. Y.

SHOE REST.

1,416,823.

Specification of Letters Patent. Patented May 23, 1922.

Application filed September 21, 1921. Serial No. 502,914.

To all whom it may concern:

Be it known that I, EPHRAIM S. HECHT, a citizen of the United States, residing at New York, in the county and State of New York, have invented certain new and useful Improvements in Shoe Rests, of which the following is a full, clear, and exact specification.

This invention relates to shoe rests or supports for display purposes, and has for its object to provide a device of this kind which is adapted to support a pair of shoes of any size in proper relative position and so that they will present an attractive and pleasing appearance.

Another object is to produce a shoe rest or display rack which is simple in construction, inexpensive to manufacture and is capable of adjustment to accommodate different sizes of either men's, ladies' or children's shoes, so that the shoes of any pair may be adjusted at a desired distance apart and at a desired angle. A further object is to insure the maintenance of the shoes in the desired set positions. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:—

Figure 1 is a plan view of a shoe rest or display rack constructed substantially in accordance with this invention, a pair of shoes being indicated in dotted lines in one position thereon.

Figure 2 is a side view of said shoe rest, showing one shoe in dotted lines supported thereon, and

Figure 3 is a detailed perspective view of one of the adjustable heel supporting members of the device.

In the embodiment of the shoe rest herein illustrated 1 designates a bridge member preferably made of rigid metal and having a curved or bowed portion 13 provided with a longitudinal slot 4 to adapt the rest to be secured at different inclinations on any suitable stand, not shown. At one end of the bridge member a cross bar 2 is secured in any suitable manner, the same extending a considerable distance at either side of said

bridge member and being designed for supporting the toe portions of a pair of shoes, as indicated in Figures 1 and 2.

To the other end of the bridge member 1 another cross bar 3 is suitably fastened so as to also extend a considerable distance at either side of said bridge member for supporting the heels of the pair of shoes, the latter being preferably arranged on the rest 65 in balanced positions at opposite sides of the bridge member as suggested in Figure 1. Said cross piece or bar 3 has an upwardly turned flange 5 at its inner edge at each end to form a stop for the adjustable heel engaging members 6 two of which are provided to extend along the opposite end portions of the bar 3 from the center thereof.

Each of the members 6 has a longitudinal slot 9 in its inner end portion to adjustably fit over a bolt 10 passed through the central portion of the bar 3. Said bolt may be fitted with a washer 12 or its head may be made large enough to straddle the slots 9 in the members 6, and the lower end of the bolt is 80 fitted with a thumb nut 11 by means of which the members 6 may be clamped in any desired adjustment on the cross bar 3. The slots 9 may be of suitable length to permit the members 6 a wide range of adjustment 85 along the bar 3.

Each of the members 6 is also provided with an upwardly turned flange or lug 7 at its inner edge, and from each of said lugs there is cut and bent a sharp tooth 8 which 90 lies preferably in a plane parallel to the members 6 and at a distance above the same, so that said teeth 8 of the respective members 6 are adapted to slightly pierce the inner faces or edges of the heels of a pair 95 of shoes as indicated in Figure 2, said teeth preferably engaging said faces or edges of the heels about midway between the top and bottom of the latter.

It will be noted that by adjusting the 100 members 6 on the cross bar 3 the teeth 8 may be arranged at different distances apart so as to engage the heels of pairs of shoes of different sizes at the proper points for properly balancing said shoes on the rest of stand. 105 By causing said teeth to slightly pierce the inner faces of the heels the shoes will be maintained in the proper set positions against accidental displacement by jars or the like.

It will also be observed that the flanges 5 on the ends of the bar 3 are spaced apart

opposite the bolt 10, leaving a space 14 which will permit said members 6 to be swung or turned on said bolt, if desired, to occupy various angular positions should such adjustments contribute to the proper arrangement or balancing of the shoes on the rest.

I claim:—

1. In a shoe rest, the combination with a cross bar for supporting the heels of a pair 10 of shoes, of devices to engage the inner faces of said heels for holding the shoes in position, said devices being adjustable on said bar for accommodating different sizes of shoes.

15 2. In a shoe rest, the combination with a cross bar for supporting the heels of a pair of shoes, of devices to engage the inner faces of said heels for holding the shoes in position, said devices being adjustable longitudinally on said bar for accommodating different sizes of shoes.

3. In a shoe rest, the combination with a cross bar for supporting the heels of a pair of shoes, of devices to engage the inner faces 25 of said heels for holding the shoes in position, said devices being adjustable longitudinally and angularly on said bar for accommodating different sizes of shoes.

4. In a shoe rest, the combination with a cross bar for supporting the heels of a pair 30 of shoes, of heel engaging devices adjustable on said bar for accommodating different sizes of shoes, and abutments for said devices at the inner edge of said bar.

35 5. In a shoe rest, the combination with a cross bar for supporting the heels of a pair of shoes, of heel engaging devices adjustable

longitudinally and angularly on said bar for accommodating different sizes of shoes, and means on said bar for limiting the angular 40 adjustment of said devices in one direction.

6. In a shoe rest, the combination with a cross bar for supporting the heels of a pair of shoes, of a bolt projecting from the central portion of said bar, engaging members 45 having longitudinal slots adjustably fitted on said bolt for accommodating different sizes of shoes, said heel engaging members having lugs extending longitudinally thereof, and means on said lugs for engaging the 50 inner faces of the heels of the shoes.

7. In a shoe rest, the combination with a cross bar for supporting the heels of a pair of shoes, of heel engaging members angularly adjustable on said bar from a common 55 point thereon, abutments on said bar for limiting the angular adjustment of said members in one direction, said abutments being spaced apart opposite the point of adjustment of said members for the purpose 60 specified.

8. In a shoe rest, the combination with a transverse support for a pair of shoes, of upwardly extending flanges on said support, teeth on said flanges to engage the inner 65 faces of the heels of the shoes, and means for adjusting said flanges longitudinally on said support to vary the relative positions of the teeth thereon for accommodating pairs of shoes of different sizes. 70

In testimony whereof I have signed my name to this specification.

EPHRAIM S. HECHT.
